CLAIM

The ornamental design for a tire for a car, as shown and described.

DESCRIPTION

FIG. 1 is a perspective view of a tire for a car, showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof.

FIG. 8 is an enlarged partial view thereof; and,

FIG. 9 is a cross section view thereof taken through line 9—9 in FIG. 8.
